United States Patent Office.

OLIVER HAWLEY AND JAMES W. WARD, OF WHEELING, WEST VIRGINIA.

Letters Patent No. 66,285, dated July 2, 1867.

IMPROVEMENT IN CHURNS.

The Schedule referred to in these Letters Patent and making part of the same.

TO ALL WHOM IT MAY CONCERN:

Be it known that we, OLIVER HAWLEY and JAMES W. WARD, of Wheeling, county of Ohio, State of West Virginia, have invented a new and useful Improvement on a Machine for Making Butter; and we do hereby declare that the following is a full, clear, and exact description of the construction and operation of the same, reference being had to the annexed drawings, making a part of this specification—

Figure 1 being a perspective view.

Figure 2 a longitudinal section, and

Figure 3 a transverse section.

Our invention consists in the employment of agitators, straight or fluted or otherwise, made stationary inside of churn for agitating the cream. The motion, as applied, which is oscillating upon end, centres the balls and springs which facilitate the working of the churn, as will be hereinafter described.

A, in each figure, is the churn oscillating on the two balls C C inside the frame B, rendering the working of the churn very easy. D D are two springs fastened on each side of frame B for the stops E E to strike against, for the purpose of stopping the motion of the churn and to give it a more sudden start on the reverse motion, thereby causing a more violent agitation in the cream. H is a lever for giving the churn motion. F, in figs. 2 and 3, are the agitators made stationary inside of churn, which act as breakers on the currents of cream, so breaking and mixing it that butter is produced more speedily.

What we claim as our invention, and desire to secure by Letters Patent, is—

The agitators F F F F, also the combination of the springs D, stops E, and balls C, operating in the manner and for the purpose described.

OLIVER HAWLEY,
J. W. WARD.
